Inventor:

Charles C. Abbott,

by *Alfred S. Davis*
His Attorney.

UNITED STATES PATENT OFFICE.

CHARLES C. ABBOTT, OF PITTSFIELD, MASSACHUSETTS, ASSIGNOR TO GENERAL ELECTRIC COMPANY, A CORPORATION OF NEW YORK.

IMMERSION HEATER.

Application filed June 16, 1922. Serial No. 568,697.

To all whom it may concern:

Be it known that I, CHARLES C. ABBOTT, a citizen of the United States, residing in Pittsfield, in the county of Berkshire, State 5 of Massachusetts, have invented certain new and useful Improvements in Immersion Heaters, of which the following is a specification.

My invention relates to immersion heaters 10 and has for its object the provision of improvements in electric immersion heaters.

In carrying out my invention I use an electric heating unit of the "sheath wire" type. In heating units of this type the resistance conductor is embedded in a compacted mass of insulating material enclosed by a metallic sheath. Such units are inherently impervious to moisture, may be readily bent to any desired form and are 20 otherwise adapted for use as an immersion heater. In one form of my invention I mount the sheath wire heating unit on a support adapted to close an opening through which the heating unit is inserted into the receptacle to contain the liquid to be heated. In one embodiment of my invention I use 25 a "helical core" sheath wire heating unit such as described and claimed in my Patent No. 1,367,341, dated Feb. 1, 1921. In such units the resistance conductor is shaped in the form of a helix whereby a much greater heating effect for a given length of heating unit may be obtained than with the usual straight resistance conductor.

For a better understanding of my invention reference should be had to the accompanying drawing in which Fig. 1 is a view partially in section of an electric immersion heater embodying my invention; Fig. 2 is 40 a partial section view of Fig. 1; while Figs. 3 and 4 are modified forms of the electric heater shown in Fig. 1.

Referring to Figs. 1 and 2 of the drawing, in one form of my invention the sheath wire heating unit 10 is bent on itself or doubled over in the shape of a hairpin and has its ends secured to and extending through a screw plug 11. The heating unit is of the helical core sheath wire type, such as described and claimed in my Patent No. 1,367,341. The resistance conductor 12 is shaped in the form of a helix and is embedded in the heat refractory insulating material 18 com-

pacted to a hard dense mass within the metallic enclosing sheath 14. As described in my aforesaid patent, the sheath 14 is formed from a length of tubing, the insulating material being compacted by reducing the diameter of the sheath by swaging. The heating unit is therefore throughout its 60 length completely impervious to moisture. The plug 11 may be a standard pipe plug, having threads 15 adapted to fit in any standard tapped opening of a corresponding diameter.

The heating element 10 is provided with terminal lugs 16 and 17, such as described and claimed in my Patent No. 1,494,938 dated May 20, 1924. In assembling the heating unit to the plug 11 the ends of the 70 heating unit, preferably before the terminal lugs 16 and 17 are attached, are inserted through parallel bores 18 and 19 in the plug. The ends are inserted through the bores in such direction that they project 75 from the outer end of the plug. The terminal lugs 16 and 17 are secured in place, for example, by swaging as described in my aforesaid patent, and seated tightly on insulating washers 18' and 19' so as to seal 80 the ends of the heating unit against the entrance of moisture. Either before or after the terminal lugs are applied, the plug is moved to its proper position near the ends of the heating unit and secured by making 85 brazed or soldered joints 20 and 21. As shown in the drawing, the plug is secured closely adjacent the insulating washers 18' and 19'. The plug is provided with a short 90 rim 22 over which fits a protecting cap 23 for the terminals. This cap is provided with a central aperture 24 through which the electrically conducting leads (not shown) connected to the terminals may extend.

As thus constructed the electric heater is adapted to be applied to the receptacle in which the liquid is to be heated by inserting the heating unit 10 through a suitable tapped opening in the receptacle and then 100 screwing the plug tightly in the tapped opening so as to make a leak-proof connection. The heating unit 10 thus extends within the receptacle in position to be immersed in the liquid to be heated. It will 105 be observed that this arrangement of the

heating unit provides for convenience both in putting the electric heater in place and in sealing the containing vessel. The heater may also be easily removed at any time for 5 repairs or replacements.

In the modification shown in Fig. 3 the heating unit 10 is twisted in the form of a double helix. This form provides for the concentration of the heating effect into a 10 much smaller space. In the modification shown in Fig. 4, two heating units 10 are mounted on a single plug. These heating elements are preferably provided with separate terminals and connections whereby they 15 may be connected in series or parallel relation in a well-known manner so as to regulate the amount of heat produced. Obviously, various other arrangements and configurations of the heating unit may be used.

20 While I have described my invention as embodied in concrete form and as operating in a specific manner in accordance with the provisions of the patent statutes, it should be understood that I do not limit my invention thereto, since various modifications 25 thereof will suggest themselves to those skilled in the art without departing from the spirit of my invention, the scope of which is set forth in the annexed claims.

What I claim as new and desire to secure 30 by Letters Patent of the United States, is:—

1. An electric immersion heater comprising 35 a metallic support adapted to close an aperture in a containing receptacle, a metallic sheath soldered to said support so as to form a water-tight connection therewith, a resistance conductor in said sheath, and powdered heat refractory insulating material compacted in said sheath around said resistance conductor so as to freely conduct 40 heat from said resistance conductor to said sheath.

2. An electric immersion heater comprising 45 a metallic screw plug provided with apertures, a metallic sheath bent on itself and having its ends extending through said apertures and soldered therein to form a water-tight joint, a resistance conductor in said sheath, and powdered heat refractory insulating material in said sheath compacted 50 to a hard dense mass in said sheath and around said resistance conductor so as to freely conduct heat from said resistance conductor to said sheath.

In witness whereof, I have hereunto set 55 my hand this 14th day of June, 1922.

CHARLES C. ABBOTT.
